ATTENUATING AND SELECTING CIRCUITS

Rothwell E. Smith, Westfield, N. J., and Leo A. Kelley, Jackson Heights, N. Y., assignors to International Communications Laboratories, Inc., New York, N. Y., a corporation of New York

Application January 23, 1931. Serial No. 510,676

3 Claims. (Cl. 178—44)

This invention relates to electrical signalling systems and more particularly to apparatus for selecting and attenuating electrical energy of various frequencies transmitted over a common line.

It is well known that the frequencies of separate channels in traversing a line may arrive at the receiving point at unequal energy levels. When one considers that receiving apparatus is generally so designed that it operates most satisfactorily at some particular energy level, which in practice is not necessarily obtainable under ordinary working conditions, one can readily perceive that suitable means for adjusting the energy level as required in the different receiving channels should be provided. If the energy level is right for one channel it may be too high or too low for other channels, and therefore suitable regulating means should be included.

It is one of the objects of this invention to provide a new and improved arrangement for attenuation purposes with the necessary regulating elements incorporated in the individual receiving circuits, and capable of adjustment as the particular frequency and other conditions of each channel may demand.

Another object is to provide means by which the operator at the receiving terminal may easily obtain the most efficient signalling voltage impressed on the demodulator.

A further object is to provide means for controlling the energy input to the receiving equipment during actual working periods.

Still another object is to provide an attenuating device whereby attenuation is obtained in a particular channel independently of other receiving channels.

Additional objects and advantages of this invention will be apparent from the following description, taken with the accompanying drawing, wherein:

Figure 1 is a graph showing the relation between transmission loss and frequency in several typical receiving channels having different carrier frequencies;

Figure 2 shows a number of receiving channels of a carrier current signalling system employing an attenuator for accomplishing the results above described.

The same numerals identify the same parts throughout.

In Figure 1 curves A, B and C show relative transmission characteristics of electrical energy coming over a typical line and delivered to a

number of receiving channels; for example, three arranged to select carrier frequencies F1, F2 and F3. The relative levels of the energy received by the various channels are indicated by the points f1, f2 and f3 upon the line XY. Assume that the line X'Y' represents the levels or intensity of incoming signal energy most suitable for the aforesaid three channels of the receiving apparatus. It will be noted that the energy received in the channel working on frequency F1 is not sufficiently attenuated; channel working on the next higher frequency F2 by a coincidence is of the right amount; and channel working on the frequency F3 is attenuated too much. By means of the appliance herein described, the channel working on frequency F1 whose characteristic curve is shown by A, can be affected so that this curve is shifted to the position A'. This is accomplished by increasing the transmission loss in this channel, as by adding attenuation with the attenuator unit, to be presently described, thus moving FA on the line XY to the position FA' on the line X'Y'. This is accomplished without changing the shape of the curve A.

In the case of the channel working on frequency F2, in connection with which characteristic curve B and the desired curve B' are identical, no adjustment is required.

The channel working on frequency F3 however, for which the curve C is the characteristic, is affected so that its curve is shifted downward and FC now falls at FC' on line X'Y'; but the curve C' still has the same shape as the curve C. This result is accomplished by reducing the effect of the attenuator, which is assumed to have some suitable initial adjustment. Thus it can be seen that the level of the energy passed on to the receiving apparatus is caused to be of the same amount in all the receiving channels; and this amount is calculated as most suitable for efficient operation.

Figure 2 shows a number of receiving channels of a carrier signalling system employing an attenuator device in each channel, for securing the results described above. Three channels 1, 2 and 3 are associated with main line ML. Since all of the channels are alike, it will be sufficient to describe in detail the component parts on one channel, namely 1. This channel contains 105 coupled-tuned circuits, 4 and 5 connected on the input side in parallel with the input circuits of the other channels. The terminals of the tuned circuit 5 are connected across the free terminals of X and Z of a continuously adjustable resist-

ance attenuator, consisting of continuously adjustable resistances X, Y and Z. The terminals of Y and Z are connected through similar tuned circuits 6 and 7 to the receiving device. Such a resistance network, as is well known in the art, can be so constructed that, for various values of resistances X, Y and Z, various transmission losses can be adjusted at will in the circuit where it is inserted. Furthermore, it can be so designed that it does not alter substantially the impedance relation, for the range of frequencies assigned to the particular channel, between the tuned input circuits 4 and 5 and the tuned output circuits 6 and 7 of the attenuator. This property is essential in order that the overall characteristic curve of any receiving channel will not be changed in shape when the attenuator is adjusted to different values and is secured by designing the input impedance of the attenuator to equal the output impedance of the tuned circuits 4 and 5; and the output impedance of the attenuator to equal the input impedance of the tuned circuits 6 and 7. By impedance of the circuits 4 and 5 or 6 and 7 is meant the impedance of each pair of circuits as a unit. When these conditions are fulfilled adjustments of the attenuator result merely in a vertical shifting of the characteristic curve, without change of shape.

The circuits may of course be balanced by inserting condensers and resistances in both sides of the various receiving channels.

It is to be understood that the coupled tuned circuits referred to above are so designed that certain practical advantages result; such as, economy of construction and uniform impedance in the various channels. The latter feature obviously permits the design of an attenuator unit which may be used interchangeably in all of the channels. The economy of construction is secured mainly by designing the tuned selecting circuits to permit the use of an inter-changeable coil for all of the inductances used in all the various channels. When this method of design is employed the selecting circuit units for the various channels are of identical construction and differ for different channels only in the size of the condensers and the amount of coupling between the pairs of inductance coils for which adjustments are easily provided in the selecting circuit units.

It can be seen that, with this invention, we can obtain a device which affords signalling currents of uniform quality in circuits having uniform impedance characteristics. Furthermore, we are enabled to secure selecting and attenuating units which, in a signalling system having a plurality of channels, may be used interchangeably in all the various channels in the manner described above. Although we prefer to associate the attenuator units with tuned circuits of this character, we of course, do not wish to be limited to devices of this precise nature in the practice of our invention.

65

70

75

Although we prefer tuned circuits of the character above described, we of course do not wish to be limited to devices of this precise nature in the practice of our invention. For example, the various channels need not be in multiple, but may be otherwise joined to the line ML.

In conclusion it should be pointed out that the above description covers only one use to which the device might be put. There may also be in a carrier current signalling system inequalities in the transmission characteristics arising from various causes. It is readily apparent that the inequality in energy levels at the various channel frequencies can be corrected, provided the device is designed to take care of the maximum variation.

What is claimed is:

1. In a carrier telegraph system, a line, signal receiving apparatus, an attenuation device for attenuating without distortion signals received over said line, said device having an input circuit tuned to select a predetermined frequency band and coupled to said line and an output circuit tuned to select the same frequency band and coupled to said receiving apparatus, and a common resistance shunting each of said circuits, the input impedance of said device being adapted to match the terminal impedance of said line and the output impedance thereof being adapted to match the input impedance of said receiving apparatus.

2. In a carrier telegraph system, a line, signal receiving apparatus, an attenuation device for attenuating without distortion signals received over said line, said device having an input circuit tuned to select a predetermined frequency band and coupled to said line and an output circuit tuned to select the same frequency band and coupled to said receiving apparatus, and a common and variable resistance shunting each of said circuits, the input impedance of said device being adapted to match the terminal impedance of said line and the output impedance thereof being adapted to match the input impedance of said receiving apparatus.

3. In a carrier telegraph system, a line, signal receiving apparatus, an attenuation device having a balanced input circuit tuned to pass a predetermined frequency band and coupled to said line and a balanced output circuit tuned to pass the same frequency band and coupled to said receiving apparatus, the input impedance of said device being adapted to match the terminal impedance of said line and the output impedance of said device being adapted to match the input impedance of said receiving apparatus, and a variable resistance coupling said circuits together, said device being adapted to attenuate signals transmitted on frequencies within said predetermined band with the same amount of impedance throughout said frequency band.
